UNITED STATES PATENT OFFICE.

LAWRENCE M. ALMASY AND ALBERT J. SMITH, OF PITTSBURGH, PENNSYLVANIA.

STEAM TURBINE.

Application filed October 12, 1922. Serial No. 594,016.

Our invention relates to new and useful improvements in single stage rotary steam turbines, more particularly to steam turbine blades therefor, and the primary object of 5 the invention is to provide a blade of the type stated, in a manner as hereinafter set forth, which is formed with recessed portions adapted for the engagement and retardation of the steam from the admission 10 nozzles on its passage around said blades thereby augmenting the impetus imparted by the driving medium and increasing the efficiency of the turbine.

Further objects of the invention are to 15 provide a turbine blade of the novel construction described, which is simple in its construction and arrangement, which may be embodied in either the moving or stationary 20 blades of the turbines, strong, durable and efficient in its use, and inexpensive to manufacture.

With the foregoing and other objects in view, which will appear as the description proceeds, the invention resides in the combination and arrangement of parts, and in the detail of construction hereinafter described and claimed, it being understood that changes in the precise embodiment of the invention disclosed can be made within the 25 scope of the claims hereunto appended without departing from the principle of the invention.

In the drawing forming a portion of this specification and wherein like numerals of 30 reference designate corresponding parts throughout the several views:—

Figure 1 is a perspective view of a turbine blade in accordance with our invention.

Figure 2 is a side view thereof.

Figure 3 is a sectional view on line III—III, Figure 2.

Figure 4 is a side view of a modified form of the device.

Figure 5 is a sectional view on line V—V, Figure 4.

Referring in detail to the drawing 1 denotes the body portion of the turbine blade formed integrally with a shank 2 by which the blade is secured in position in the revolving barrel of the turbine.

The general contour of the body portion 5 of the body portion 1 is similar to turbine blades now commonly used and are radially disposed in circumferential alignment in proximity to each other on the revolving barrel of the turbine. The body portion 1 together with the

shank 2 is formed with a radially aligned concaved forward face 3 and a corresponding convexed rear face 4 to permit of interengagement of adjacent blades upon the barrel of the turbine.

The convexed rear face 4 of the body portion 1 is recessed to provide a convex wall 5, which in conjunction with the concaved forward face of the adjacent blade assembled thereagainst, forms a passage-way for the driving medium, namely steam, etc. The outer end 6 of the body portion serves to confine the driving medium to the passage-way. The driving medium is directed from the steam admission nozzles to enter the passage-way at one side of the blades and impact against the concave faces 3 of the blades to impel the turbine barrel, after which it is exhausted through the passage-way at the other side of said blades.

The side of the blade wall at which the driving medium or steam enters is formed with a pocket 7. The length, depth, contour or angular disposition of the pocket 7 may 80 be such as to best meet conditions found in practice, but relatively to its depth is preferably formed to extend parallel to the concave face 3 of the body portion 1.

In the use of our improved blade, the driving medium will not only impact against the concave face 3, of the blade in the usual manner but will also impact in the pocket 7 thereof. As the pocket 7 provides additional impacting area for the driving medium, the 90 power of the latter is proportionally increased resulting in a more efficient turbine.

The modification of the turbine blade illustrated in Figures 4 and 5, of the drawing is identical in construction and operation 95 as that described relative to the preferred form, with the exception that two pockets 7' are formed in the wall 5' instead of one such pocket. It will be obvious that a plurality of pockets may be successfully employed in the construction of our improved turbine blade.

While our improved turbine blade is primarily intended for use in single stage steam turbines, it will be obvious that the same 105 may be employed in connection with any type of turbine wherein it is found to be applicable.

What we claim is:—

1. A turbine blade comprising a body 110 portion provided with a shank and having a recessed rear wall, one of the side walls

of said body portion being formed with a pocket.

2. A turbine blade comprising a body portion provided with a shank and a side wall formed with a pocket.

3. In a turbine blade comprising a body portion provided with a shank and having a recessed rear wall, a pocket formed in one side of said body portion and disposed forwardly of the recessed rear wall.

4. In a turbine blade having a concave forward face and a corresponding convex rear face, a portion of said rear face being recessed, a pocket formed forwardly of the recessed portion of said rear wall and at one side thereof.

In testimony whereof we affix our signatures.

LAWRENCE M. ALMASY.
ALBERT J. SMITH.
